UNITED STATES PATENT OFFICE

ANTHONY E. WALLER, OF PROVIDENCE, RHODE ISLAND

JOINT FOR PIN STEMS

Application filed December 4, 1929. Serial No. 411,491.

This invention relates to an improved construction of joint for pin stems; and has for its object to provide a joint member of this character which is constructed with one or 5 more outwardly-extending fingers formed on the forward edge of one or both of the ears, the fingers being inclined inwardly or toward each other and positioned to provide a fulcrum for the pinstem located a substantial 10 distance outward from the forward edge of the side ears.

With these and other objects in view, the invention consists of certain novel features of construction, as will be more fully described, and particularly pointed out in the appended claims.

In the accompanying drawings:

Fig. 1 is an elevation of the joint member partly in section showing the base or bridge portion of the joint as soldered to the base plate.

Fig. 2 is a view of the joint member in extended position.

Fig. 3 shows the joint in end elevation with 25 both its side ears and fulcrum fingers folded into working position.

Fig. 4 is the same as Fig. 3 showing the pinstem in section as mounted upon the joint ears and bearing on the fulcrum fingers.

30 Fig. 5 is a top view of the joint member with the pinstem removed, showing the fulcrum fingers as extending outwardly from the edge of the joint ears to provide a fulcrum positioned a substantial distance forward of 35 these pivot ears.

Fig. 6 is a top view showing the pinstem as sprung off to one side upon entering the catch member, and showing its position when engaging the fulcrum fingers under its greatest binding stress.

It is found in the practical construction and 45 operation of joint members for pinstems, particularly those of the smaller sizes, of advantage to form the fulcrum arms integral with the pivot ears and arrange them to extend the fulcrum point for the pinstem as far away from the pivoting point as possible without causing the joint member to look too large and clumsy, which extended position of the 50 fulcrum gives a better support to the pinstem

and increases the effectiveness of its spring or resiliency to better retain its pointed end in its catch member; and the following is a detailed description of the present embodiment of my invention and showing one arrangement of fulcrum fingers by which these 55 advantageous results may be accomplished.

With reference to the drawings, 10 designates my improved catch member which is provided with a short bridge portion 11 which 60 has side ears 12 formed integral therewith and folded to extend upwardly from opposite edges thereof.

This bridge member serves as a suitable base or support to be soldered in position on 65 the base plate 13 of the pin. The joint ears 12 may be pierced or they may have inwardly-extending pivot projections 14 which cooperate to provide between them a suitable pivot which extend from opposite sides into the 70 eye 15 of the pinstem 16 on which it swings.

In mounting a pinstem in a joint member, it is of course, essential that some means be provided against which the pinstem will fulcrum, and it is found particularly in joints 75 of the smaller sizes, to be applied to delicate jewelry, that these joint members should be kept as small as possible so as not to look cumbersome or bulky on this delicate jewelry; and particularly in joint members of 80 these small sizes, it is found of advantage to form the fulcrum of a pair of fingers 19, each of which is formed integral with the forward edge of its pivot ear, and that it is of advantage to position this fulcrum point 20 as far 85 from the pivot point as possible, I have formed these fingers of a length considerably greater than one-half the distance between the ears when folded into working position and I have curved these extending fingers so 90 that they may abut each other and provide a fulcrum a substantial distance outwardly or forwardly from the forward edges of the pivot ears.

In practice the outer ends of these fingers 95 may or may not abut. As illustrated in Fig. 6, this pinstem is under its greatest strain while its pointed end is being passed around its point 17 of the catch 18, at which time this pinstem is swung off to one side and at a con- 100

siderable distance from its normal working axis thereby carrying its fulcrum point to one side of the center of the bearing portion of these fingers.

5 By my improved construction, I am enabled to provide a pinstem joint which is very neat in appearance and which by the arrangement of its fulcrum arms provides a fulcrum point for the pinstem a substantial distance forwardly from the pivoting center of the pinstem thus providing the maximum support for the pinstem to assist the resiliency of the pin to prevent inadvertent disengagement from its catch member in which the pointed end of the pinstem is housed.

10 15 I do not wish to limit myself to the use of a pair of arms, one on each ear, as in some instances a single arm, may be employed as a fulcrum for the pinstem.

20 25 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

30 35 1. A pinstem joint of sheet stock shaped and folded to form a short bridge and attaching base portion and having two spaced upstanding side ears integral therewith between which ears a pinstem may be pivotally mounted, and a fulcrum finger extending outwardly from the forward edge of one of

35 40 said side ears and inclined inwardly toward a center line between said ears to provide a fulcrum for the pinstem which is located a substantial distance beyond the forward edge of said ears.

40 45 2. A pinstem joint of sheet stock shaped and folded to form a short bridge and attaching base portion and having two spaced upstanding side ears integral therewith between which ears a pinstem may be pivotally mounted, and a pair of fingers formed on the forward edge of said ears to extend outwardly therefrom and inclined toward each other, said fingers providing a fulcrum for the pinstem located a substantial distance beyond

50 the forward edge of said side ears.

50 55 3. A pinstem joint of sheet stock shaped and folded to form a short bridge and attaching base portion and having two spaced upstanding side ears integral therewith between which ears a pinstem may be pivotally mounted, and a pair of fingers formed on the forward edge of said ears to extend outwardly therefrom and inclined toward each other, the combined length of said fingers being

60 greater than the working distance between said ears, said fingers providing a fulcrum for the pinstem located a substantial distance beyond the forward edge of said side ears.

In testimony whereof I affix my signature.

65 ANTHONY E. WALLER.
